UNITED STATES PATENT OFFICE.

JOHN R. THOMLINSON, OF PARTICK, GLASGOW, SCOTLAND.

DESIGN FOR A LEATHER FOOTBALL-COVER.

58,167.

Specification for Design.

Patented June 14, 1921.

Application filed September 14, 1920. Serial No. 410,339. Term of patent 14 years.

To all whom it may concern:

Be it known that I, JOHN ROBERTSON THOMLINSON, a subject of the King of Great Britain and Ireland and the Isle of Man, and a resident of Partick, Glasgow, Scotland, leather-goods manufacturer, have invented a new, original, and ornamental Design for Leather Football-Covers, of which the following is a specification, reference being made to the accompanying drawings.

Figures 1 and 2 are views at right angles

to each other of a football cover made in accordance with my design.

The cover is composed of ten similarly shaped panels.

I claim:

The ornamental design for a leather football cover, as shown and described.

JOHN R. THOMLINSON.
